US0D1086702S

(12) United States Design Patent (10) Patent No.: US D1,086,702 S
(45) Date of Patent: * Aug. 5, 2025

(54) HANDBAG

(71) Applicant: BOTTEGA VENETA S.R.L.,
Montebello Vicentino (IT)

(72) Inventor: Matthieu Blazy, Milan (IT)

(73) Assignee: BOTTEGA VENETA S.R.L.,
Montebello Vicentino (IT)

() Term: 15 Years

(21) Appl. No.: 29/970,331

(22) Filed: Oct. 28, 2024

(30) Foreign Application Priority Data

Apr. 30, 2024 (EM) 015059382-0014

(51) LOC (15) Cl. 03-01

(57) CLAIM

The ornamental design for a handbag as shown and described.

DESCRIPTION

FIG. 1 is a perspective view of a handbag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective close-up view of the handbag as shown in FIG. 1;

FIG. 9 is a front close-up view of the handbag as shown in FIG. 2;

FIG. 10 is a back close-up view of the handbag as shown in FIG. 3;

FIG. 11 is a left side close-up view of the handbag shown in FIG. 4; and,

FIG. 12 is a right side close-up view of the handbag as shown in FIG. 5.

The longer broken lines in the drawings represent portions of the bag that form no part of the claimed design. The shorter broken lines in the drawings represent stitching that forms no part of the claimed design.

1 Claim, 12 Drawing Sheets
